UNITED STATES PATENT OFFICE.

SEmen SYNOHUBYK, OF MYRNAM, ALBERTA, CANADA.

PROTECTIVE MASK.

1,224,039.

Specification of Letters Patent. Patented Apr. 24, 1917.

Application filed November 27, 1916. Serial No. 133,765.

To all whom it may concern:

Be it known that I, SEMEN SYNOHUBYK, a subject of the King of England, residing at Myrnam, in the Province of Alberta and 5 Dominion of Canada, have invented certain new and useful Improvements in Protective Masks, of which the following is a specification.

This invention relates to masks and has 10 special reference to a protective mask designed to protect the wearer against the inhalation of noxious or poisonous fumes and gases as well as to afford protection against lachrymal gases and corrosive fluids.

15 One object of the invention is to improve and simplify the general construction of devices of this character.

A second object of the invention is to provide an improved mask of this character 20 which, while permitting free exhalation from the nostrils will only permit inhalation through the mouth, the opening for the latter being covered by gas absorbent or counteracting material so arranged as to be 25 readily swung aside for talking, feeding and the like.

A third object of the invention is to provide an improved construction of mask having 30 elastic portions so positioned and arranged that it may be fitted to any sized head, the elastic portions being protected from undue stresses by a novel arrangement of relatively inelastic draw laces.

With the above and other objects in view, 35 as will be hereinafter apparent the invention consists in general of certain novel details of construction and combinations of parts hereinafter fully described, illustrated in the accompanying drawing, and 40 specifically claimed.

In the accompanying drawing, like characters of reference indicate like parts in the several views, and:—

Figure 1 is a side view of the mask in use 45 on a wearer.

Fig. 2 is a front view of the mask laid out flat.

Fig. 3 is a vertical median section through the mask on a wearer's head.

50 In the embodiment of the invention herein illustrated there is disclosed a mask having a front or face portion 10 to which are connected, by means of elastic strips 11, the side portions 12. These side portions have 55 extensions 13 which are connected behind

the head by snap fastenings 14. The portions 10 and 12 are also connected by lacings 15 so that, by proper adjustment of these lacings the elastic strips may be prevented from stretching so far that they tear 60 or break.

Beneath the portion 10, and formed integrally therewith is a mouth and chin portion 16 terminating in neck straps 17 adapted for connection by fasteners 18. These 65 straps 17 also have elastic webbing 19 interposed in their lengths.

The body 10 is provided with eye openings covered by the glasses 20 and with a nose opening covered by a protector 21 having a breathing opening 22 closed against the admission of air by a valve 23 normally held closed by a light spring 24 which yields readily upon exhalation to permit the valve 75 to open.

Covering the mouth opening 25 is a reticulated basket 26 pivoted at one end to a pivot 27 and provided at its other end with a hook 28 engageable over a headed pin 29. By means of this arrangement the hook may 80 be raised and then the hook provided end of the basket may be sprung out and dropped to afford free access to the mouth opening. The basket is preferably filled with absorbent material 30 which may be moistened 85 with a suitable chemical to absorb or neutralize any poisonous or noxious fumes or gases.

The whole mask is bound with a peripheral cushion 31 to cause it to fit closely. 90

There has thus been provided a simple and efficient device of the kind described and for the purpose specified.

It is obvious that many minor changes may be made in the form and construction 95 of the invention without departing from the material principles thereof. It is not therefore desired to confine the invention to the exact form herein shown and described but it is wished to include all such as properly 100 come within the scope claimed.

Having thus described the invention, what is claimed as new, is:—

1. A mask of the class described having a front or face portion and lateral portions, 105 elastic strips connecting the face and lateral portions, means to limit the expansion of the elastic strips and means to releasably secure said lateral portions together behind the wearer's head. 110

2. A mask of the class described having a front or face portion and lateral portions, elastic strips connecting the face and lateral portions, lacings crossing said elastic strips and limiting the expansion thereof, and means to releasably secure said lateral portions together behind the wearer's head.

In testimony whereof I affix my signature in the presence of two witnesses.

SEMEN SYNOHUBYK.
